METHOD AND APPARATUS FOR CRACKING HYDROCARBON OILS

Filed Jan. 19, 1928

UNITED STATES PATENT OFFICE

RICHARD J. DEARBORN, OF SUMMIT, NEW JERSEY, ASSIGNOR TO THE TEXAS COMPANY, OF NEW YORK, N. Y., A CORPORATION OF DELAWARE

METHOD AND APPARATUS FOR CRACKING HYDROCARBON OILS

Application filed January 19, 1928. Serial No. 247,832.

This invention relates to the conversion of higher boiling point hydrocarbon oils into lower boiling point products, and has special reference to a cracking process and apparatus of the so-called "coil and drum" type, in which the oil is decomposed or cracked by rapidly raising the temperature thereof in transit through a heating coil, and then delivering it into an enlarged drum or chamber in which cracking temperatures and pressures are maintained.

One of the objects of this invention is to provide a method and system of this general character in which the bulk of the heat employed for the cracking operation is imparted to the oil in transit through the heating coil, while the maintenance or the attainment of the desired cracking temperature is effected in a heat-insulated enlarged drum by auxiliary heat imparted by means of pipe coils enclosed within the drum, and through which coils, highly heated hydrocarbon vapors and gases, hydrogen or other vaporous or gaseous mediums are passed.

More specifically, however, an object of this invention is to provide a cracking process and system of the above indicated type, wherein the desired cracking temperature in the drum is effected by passing the highly heated vapors of a vapor-phase cracking process through coils disposed therein and in indirect contact with the body of oil in the drum.

Another object of the invention is to suspend the auxiliary heating coil from a removable cover of the drum, so that it can be readily removed for cleaning and inspection purposes.

These and other objects of this invention, and features by means of which they are attained, will be more fully understood from the following description of the process in connection with the preferred embodiment of the apparatus as illustrated in the single figure of the accompanying drawing, which is a diagrammatic view of an apparatus or system constructed in accordance with the present invention.

Referring to the drawing, the system shown comprises an elongated heating coil 1 of restricted cross-section for heating the oil

in transit, by means of a suitable furnace 2 which is fired by a burner 2^a, disposed below it. A drum 4 receives the heated oil from the coil 1 and is constructed with removable top and bottom ends or heads 4^a and 4^b. The drum 4 is heat-insulated by means of lagging 5. The heated oil emerging from the coil 1 is conducted through a heat-insulated pipe 3 and is delivered into the bottom of the drum 4. The heated oil emerging from the coil 1 may have a temperature, depending upon the charging stock, varying from 750° F. to 950° F., or even higher, but more frequently the temperature is maintained at approximately 850° F. Pressure is preferably maintained in the system, and may range from 100 to several hundred pounds depending upon conditions. A valve 7 may be interposed in the line 3 between the coil 1 and the drum 4, if desired, and may be utilized either for reducing the pressure in the drum or merely for emergency purposes in case of fire. Ordinarily, this valve 7 will be fully open. A draw-off line 8 having a valve 9 is provided in the bottom head of the drum 4.

A heat-insulated vapor line 10 permits the passage of the vapors from the drum 4 to the separator 12, wherein a separation of the lighter and heavier constituents may be effected. The lighter constituents, emerging as a vapor from the upper end of the separator 12, pass through a pipe 13 and into a water-cooled condenser 16 where the vapors are condensed and then pass through pipe 19 to enter the receiving tank 20 which is provided with a gas outlet 21 having a valve 22, and a discharge outlet 23 having a valve 24. The heavier constituents, condensed in the separator 12, are drawn off by means of pipe 14 and valve 15, and may be used for recycling to the heating coil or otherwise, as desired.

For the purpose of assisting in maintaining the desired cracking temperature in the drum 4, an auxiliary vapor-phase converter 30 of any type suitable is employed. As illustrated, this converter is of a form similar to that of the heating coil 1, that is, an elongated coil of restricted cross section, that

is highly heated by a suitable furnace 31 fired by a burner 32 disposed below it.

The vapors in the converter coil 30 are preferably subjected to pressure and to a high temperature, for example, from 1000° F. to 1300° F., whereby cracking in the vapor phase is effected therein. A temperature of around 1100° F. will ordinarily be adequate.

10 The issuing hot cracked vapors and gases are passed through a heat-insulated line 35 to a vertically disposed coil 38, which is completely enclosed within the drum 4 and is suspended from the removable cover 4^a.

15 The construction and arrangement is such that upon releasing the attaching means of the removable cover 4^a, the cover and the coil 38 may be removed as a unit from the drum, to facilitate the cleaning operation.

20 The coil 38, being subjected to the high temperatures of the cracked vapors and gases emerging from the converter 30, which continuously pass through it, thereby constitutes a heating element for the body of heated liquid contained in drum 4, in which

25 the coil 38 is wholly or partially submerged. Thus the coil imparts additional heat to the hot oil in the drum sufficient in quantity and degree to maintain the desired cracking temperatures therein by compensating for heat losses incident to radiation, decomposition and distillation, or even to raise the temperature slightly above that of the heating coil 1 to attain a somewhat higher cracking temperature, if desired.

30 Obviously, the bulk of the heat is imparted to the oil in transit through the heating coil 1, but the heat abstracted from the auxiliary vapor-phase operation is utilized for the 35 regulated maintenance of whatever cracking temperature is determined upon for the oil in the cracking drum. This regulation is accomplished by the proper control of the vapor-phase operation, as to temperature or 40 speed of flow of the products passing therethrough.

45 The highly heated vapors emerging from the coil 38 pass through a heat-insulated pipe 39, provided with a pressure-reducing valve 40, and are discharged into a separating and carbon receiving drum 43, which is heat-insulated by means of lagging 44. A draw-off 41 having a valve 42 is provided at the bottom of drum 43 for the discharge 50 for heavy tar and carbon.

55 The vapors emerging from the top of drum 43 are conducted through a heat-insulated pipe 50 into a separator 51 wherein a separation of the lighter and heavier constituents may be effected. The lighter constituents, emerging as a vapor from the upper end of the separator 51, pass through pipe 54 into a water-cooled condenser 55, where the vapors are condensed. The distillate 60 passes through a pipe 57 into a receiving

tank 59, which is provided with a gas outlet 60 having a valve 61 and a discharge outlet 62 having a valve 63. The heavier constituents condensed in separator 51 are drawn off by means of pipe 52 and valve 53, and may be used for recycling or otherwise, as desired.

70 The system and method of operation set forth provides a simple and effective way of maintaining any desired cracking temperature in the liquid-phase cracking drum, while at the same time conserving the heat of a vapor-phase cracking operation which would otherwise be wasted. Moreover, the 75 removability of the auxiliary heating coil 80 contributes to facility in the cleaning operation.

85 Although the invention, as set forth for illustrative purposes, embodies more or less specific details of construction and operation, it should be understood that many variations and modifications may be effected therein without departing from the spirit and scope 90 of the invention in the main. Therefore, only such limitations should be imposed as 95 are indicated in the appended claims.

What I claim is:

1. A process of converting higher boiling point hydrocarbon oil into lower boiling point products which comprises passing the oil through a heating coil of restricted cross section, heating the oil in transit to substantially a cracking temperature, delivering the heated oil into a cracking drum where a body of oil collects, simultaneously cracking oil 100 in the vapor-phase at a relatively high cracking temperature, and passing the cracked vapors and gaseous products thereof in indirect contact with said body of oil to maintain a cracking temperature therein and effect cracking of the oil in the liquid phase.

105 2. A process of converting higher boiling point hydrocarbon oil into lower boiling point products which comprises heating a stream of oil to substantially a cracking temperature in its passage through a heating coil of restricted cross section, delivering the heated oil into an enlarged cracking drum where a body of oil collects, maintaining a cracking temperature in said body of oil by 110 passing the hot cracked products of a simultaneously operated vapor-phase cracking operation in indirect contact therewith, and regulating the temperature of said oil body by controlling the operation of the vapor-phase cracking operation.

115 3. Apparatus for converting higher boiling point hydrocarbon oils into lower boiling point products, comprising an elongated heating coil through which oil passes in transit and is heated, a heat-insulated drum connected with the heating coil wherein a body of hot oil collects, a vapor-phase converter, an auxiliary coil enclosed within the 120 said drum and submerged in the hot oil there-

in and means for conducting the vapor-phase cracked products from said converter through said auxiliary coil to impart heat to the body of hot oil and maintain it at a cracking temperature.

4. Apparatus for converting higher boiling point hydrocarbons into lower boiling point products, comprising a heating coil of restricted cross section for heating oil in transit therethrough to a high temperature, an insulated enlarged cracking drum connected thereto for receiving the heated oil in a body, an outlet line from the upper portion of the drum for passing off vapors and an outlet line from the lower portion of the drum for passing off the liquid portion, a vapor phase cracking converter having connected thereto a coil removably suspended within the drum and means for passing porous or gaseous products from said converter at a high cracking temperature through the suspended coil to thereby maintain the oil body at a cracking temperature.

In witness whereof I have hereunto set my hand this 6th day of January, 1928.

R. J. DEARBORN.
